CHAIN SAW

Leonard M. Strunk, Coatesville, Pa.

Application September 3, 1954, Serial No. 32,154

Term of patent 14 years

(Cl. D93—3)

Figure 1 is a side elevational view of a chain saw showing my new design;

Figure 2 is a top plan view thereof;

Figure 3 is a side elevational view of the chain saw as it appears when viewed from the line 3—3 of Figure 2;

Figure 4 is an end elevational view of the saw as it appears when viewed from line 4—4 of Figure 1; and

Figure 5 is an end elevational view of the saw as it appears when viewed from line 5—5 of Figure 1.

I claim:

The ornamental design for a chain saw, as shown.
